UNITED STATES PATENT OFFICE

CHARLES A. BARRETT, OF LARCHMONT, NEW YORK

METHOD OF DECORATING ARTICLES OF HOSIERY

Application filed October 29, 1932. Serial No. 640,248.

My invention relates to a new and improved method of decorating articles of hosiery.

One of the objects of my invention is to provide a simple and improved method for decorating articles of hosiery by printing a suitable design upon the same, in one or more colors.

Another object of my invention is to provide a method whereby the articles of hosiery may be handled in large quantities.

Another object of my invention is to provide a method whereby the desired design can be clearly printed, even though the design has considerable detail.

Other objects of my invention will be set forth in the following description and drawing which illustrates a preferred embodiment thereof, it being understood that the above general statement of the objects of my invention is intended merely to generally explain the same and not to limit it in any manner.

Fig. 1 is a plan view showing a number of unprinted stocking blanks connected to a carrier fabric.

Fig. 2 is a sectional view on the line 2—2 of Fig. 1.

Fig. 3 is a view similar to Fig. 1 showing how the design has been printed upon the stocking blanks and upon the carrier fabric.

Fig. 4 is a plan view of a printed stocking blank.

Fig. 5 diagrammatically illustrates the printing operation.

It has heretofore been attempted to print upon individual stocking blanks, but this has required the use of a very expensive method in handling the individual blanks, and the printed design has not been applied or developed in a clear and uniform manner.

According to my invention a suitable number of stocking blanks 2 are affixed to a carrier fabric 1. I have illustrated the use of the ordinary flat stocking blanks which are used in making full-fashioned hosiery. The carrier fabric 1 is preferably made of closely woven cotton fabric, which has been suitably shrunk and which has little or no

elasticity or stretch in any direction. The blanks 2 are connected to the carrier fabric 1, with the longitudinal axes of the blanks parallel to the warp threads of the fabric. The carrier fabric 1 is so closely woven and shrunk that it has little or no stretch or elasticity even on the bias. The sheet of carrier fabric 1 may be several hundred yards in length, and a large number of the blanks 2 are connected thereto, said blanks being preferably arranged in longitudinal rows. While I do not wish to be limited to any particular means for connecting the stocking blanks 2 to the carrier fabric 1, I prefer to accomplish this connection by means of a releasable stitch S. This stitch is formed by cotton thread or the like, and said stitch is preferably not interlocked with the carrier fabric 1, so that the thread of the switch can be easily pulled out. The stitches S are located at the edges of the stocking blanks.

The carrier fabric 1 can absorb the printing medium very readily. For this purpose the carrier fabric 1 should be free from sizing, gum, finishing material and the like, so that it is very absorbent. Likewise, the cotton yarn from which the carrier fabric 1 is woven, should be free from projecting fuzz and projecting fibres of all kinds. The object of eliminating the gum, sizing and the like, is to render the carrier fabric 1 very absorbent, and the object of eliminating all fuzz and loose fibres from the cotton yarn, is to prevent the printed design from blurring. In order to impart these special properties to the cotton carrier fabric 1, said carrier fabric 1 may be treated at a suitably high temperature in a suitable solution of olive oil soap. For this purpose the carrier fabric 1 may be boiled in the solution of olive oil soap, and all traces of soap are removed from the fabric by suitable washing. The carrier fabric is thus completely free from all fatty impurities and addition agents, and this refers not only to the fats, waxes, or the like which are naturally present in the fibre, but also includes those materials which are added artificially during the operations of spinning and weaving.

The carrier fabric 1 is treated in the manner above mentioned before the stocking blanks 2 are connected thereto. The carrier fabric 1 has the usual white or gray color. If desired, the carrier fabric 1 could be woven from specially prepared yarn which is free from fuzz and which is very absorbent. It is also desirable that the carrier fabric 1 should be thoroughly shrunk. 5
10 The connection between the stocking blanks and the carrier fabric should be sufficiently strong to prevent the stocking blanks from stretching or creeping during the printing operation, in order to prevent distortion of 15 the design which is printed upon said stocking blank.

As there are many styles or methods of printing upon textile fabrics, I do not wish to be limited to any particular style or 20 method.

However, I prefer to use the discharge style or method of printing upon the stocking blanks, which are ordinarily made of silk, rayon, or cotton. This discharge method is the same style or method of printing which is largely used for printing silk neckties, handkerchiefs and mufflers. For this purpose the silk blanks are first suitably dyed with a ground color, and a printing 25 medium is utilized which contains a discharge of any suitable type. Likewise, I may use the resist style or method of printing in which the blanks are first treated with a suitable resist and the printing machine is 30 then utilized for applying a medium which includes acid or direct colors. Before the silk stocking blanks are placed upon the carrier, the stocking blanks are first boiled-off or finished in any suitable manner, and the 35 stocking blanks are then temporarily sewed together in stocking form, said forms are boarded or ironed by means of heat and pressure, and the temporary stitches are then removed from the stocking forms, so that the 40 blanks be flat and smooth on the carrier belt. 45

Likewise I may utilize the ingrain process in which an insoluble color is finally developed upon the silk yarn or fibre.

The silk blanks are treated in any of the 50 well known manners for the purposes of the printing operation, dependent upon the style or method of printing which is utilized. The silk blanks may be connected to the carrier fabric 1 while they are prepared for the printing, or the silk blanks may be first prepared for the printing operation, and they can be then connected to the carrier fabric 1. However, it is preferable to first connect the 55 silk blanks to the carrier fabric 1, or to connect said blanks to the carrier fabric 1 while some of the preliminary operations are being performed upon said silk blanks, because the carrier fabric 1 may be one thousand yards in length, and said carrier fabric 60 65 1, together with the connected stocking

blanks 2, may be wound upon a roller, so that the stocking blanks may be treated in exactly the same manner as though a long piece of silk or other fabric was being treated in the ordinary manner. 70

Fig. 5 conventionally illustrates a printing machine having a pressure bowl or roller 4, which is provided with lapping 5. The printing roll 8 is suitably engraved and it is supplied with the printing medium from the bowl 6 by means of the roll 7. The printing roll 8 is provided with the usual doctor blade 9 for removing surplus printing medium, and said printing roll 8 may also be provided with the usual lint doctor blade 10. 75 80

Fig. 5 also shows the usual endless printing blanket B, and the usual back gray cloth G. The usual guide rollers R are also provided. 85

Fig. 5 illustrates printing in a single color, but any number of printing rollers could be provided, if it is desired to print in a plurality of colors.

The printing medium includes dextrine or other thickening agent, so that it is applied 90 in the ordinary manner.

While the stocking blanks are being printed with any suitable design D, the carrier fabric 1 is also printed with said design.

It is much more difficult to clearly print a design which has fine detail upon a sheet of elastic knitted fabric, than upon a sheet of closely woven fabric, but the use of the special carrier cloth 1 makes it possible to accurately print very fine designs which have great detail. The special carrier cloth 1 readily absorbs the ink, so that the design does not spread upon the knit fabric. The absorptive power of the carrier cloth should at least be equal to that of the knit fabric, in order to prevent the design from spreading upon the knit fabric. Likewise, it is preferable to connect the stocking blanks to the carrier fabric by means of the thread of the stitches S, instead of using an adhesive, 100 because the use of the adhesive would interfere with the application of the printing medium. When the stocking has large loops, such as mesh stockings, the engraved design on the roller may be correspondingly 105 coarse. In a finely knit stocking, the design is fine. The printing roller may be engraved by hand, by photo-engraving, etc., and the printing may be single color or 110 multi-color. 115 120

I do not wish to be limited to this specific example, as it is merely illustrative as indicating the proper relationship between the absorption of the printing medium by the stocking blank and the absorption of said medium by the carrier fabric. 125

After the printing has been completed, the carrier fabric and the attached stocking blanks are then subjected to the usual additional processes, such as steaming, aging, 130

washing, and the like. These operations may be referred to as finishing operations, because they finish or complete the printing operation. The stocking blanks are thus finished. The stocking blanks can therefore be handled very economically because the printing, as well as the operations prior to printing and subsequent to printing, are performed while the stocking blanks are connected to the carrier fabric, so that the expense of printing upon the stocking blanks does not materially exceed the expense of printing upon a single long piece of fabric which may be one thousand yards in length.

In order to prevent the stocking blanks from being distorted while they are connected to the carrier fabric, the carrier fabric or a portion thereof may be placed in the flat condition upon a suitable table, the stocking blanks are placed in proper position upon the carrier fabric while said stocking blanks are perfectly flat and unstretched, and a moving sewing machine head is then moved around the edges of the stocking blanks so as to stitch them to the carrier fabric. For this purpose the table is provided with suitable grooves or perforations, in order to permit the sewing needle to penetrate the stocking blanks and the carrier fabric. I have not illustrated sewing machines of this type in which the head is moved while the fabric is held stationary, as such machines are well known per se to the trade, and they are used for example in stitching numbers upon pieces of fabric. After the stocking blanks have been printed and finished, they can be removed from the carrier fabric, and the carrier fabric may be bleached or otherwise treated so as to restore it to its original condition.

After the blanks are detached from the carrier fabric, their longitudinal edges may be stitched together in the usual manner for completing the stocking.

The carrier may be made of any suitable fabric, woven, knitted or felted, or from any suitable absorbent material, such as a suitable paper, etc.

I have shown a preferred embodiment of my invention, but it is clear that numerous changes and omissions can be made without departing from its spirit.

I claim:

1. In the art of printing upon stockings, that step which consists in printing upon the stocking blanks while they are stitched to a carrier made of textile fabric, the threads of said carrier fabric which contact with said blanks being substantially free from projecting fibres.

2. A method of printing upon stockings which consists in connecting stocking blanks to a carrier made of absorbent ma-

terial, and then printing upon said stocking blanks and finishing said stocking blanks subsequent to said printing operation while they remain connected to said carrier.

3. In the art of printing upon stockings, that step which consists in printing upon the stocking blanks while they are connected to a carrier made of absorbent material, said carrier having at least the same absorptive power for the printing medium as said stocking blanks.

4. In the art of printing upon a stocking blank, those steps which consist in temporarily connecting the edges of the blank so as to form a stocking, then subjecting the stocking blank to a smoothing operation, and then disconnecting the edges of the blank so that said blank lies smooth and flat and is ready for the printing operation.

In testimony whereof I affix my signature.

CHARLES A. BARRETT.
